CHARLES BOOZE, OF BUFFALO, NEW YORK, ASSIGNOR TO H. M. BIRGE & SONS,
OF SAME PLACE.

DESIGN FOR WALL-PAPER.

SPECIFICATION forming part of Design No. 21,947, dated November 1, 1892.

Application filed October 3, 1892. Serial No. 447,732. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of this design consists of an ornament of the German renaissance style and composed of a series of connected ornamental scrolls, with a vase filled with flowers arranged in the center of the ornament, as represented in the accompanying drawing. An ornament extends from the

center of the vase above the flowers and is partly hidden by the flowers.

The design is arranged at regular distances apart over the surface of the paper and is 20 printed in any desired color or in bronze upon tinted paper of any desired color.

What I claim is—

The design for wall-paper herein shown and described.

Witness my hand this 30th day of September, 1892.

CHARLES BOOZE.
